(57) CLAIM

The ornamental design for an adjustable gutter hanger bracket, as shown and described.

DESCRIPTION

FIG. 1 is a perspective view of the adjustable gutter hanger bracket of my new design, with a section of gutter therein being shown in phantom lines for illustrative purposes and forming no part of the invention;

FIG. 2 is a front elevational view thereof;

FIG. 3 is rear elevational view thereof;

FIG. 4 is a top plan view thereof;

FIG. 5 is a left side elevational view thereof, the right side being a mirror image of that shown, with movement of the handle being shown in phantom lines for illustrative purposes and forming no part of the invention; and,

FIG. 6 is a bottom plan view thereof.
